UNITED STATES PATENT OFFICE.

ROBERT G. NICHOLAS, OF CLYDE, KANSAS.

CLOTH-MEASURING MACHINE.

No. 904,078.

Specification of Letters Patent.

Patented Nov. 17, 1908.

Application filed July 9, 1908. Serial No. 442,673.

To all whom it may concern:

Be it known that I, ROBERT G. NICHOLAS, citizen of the United States, residing at Clyde, in the county of Cloud and State of Kansas, have invented certain new and useful Improvements in Cloth-Measuring Machines, of which the following is a specification.

The present invention relates to a novel device for quickly and accurately determining the length of cloth or textile fabric upon a reel or for measuring any desired amount of the cloth from the reel.

The object of the invention is the provision of a simple and inexpensive cloth measuring machine embodying a novel construction which admits of the bolts or reels of cloth being quickly applied thereto or removed therefrom as desired, and which may be adjusted so as to be utilized in connection with cloth or fabrics of various widths.

For a full understanding of the invention and the merits thereof and also to acquire a knowledge of the details of construction and the means for effecting the result, reference is to be had to the following description and accompanying drawings, in which:

Figure 1 is a side elevation of a cloth measuring machine embodying the invention. Fig. 2 is a top plan view of the same, portions being broken away. Fig. 3 is a transverse sectional view on the line 3—3 of Fig. 1. Fig. 4 is a perspective view of one of the sides of the machine. Fig. 5 is a detail view of one of the blocks for engaging one end of the bolt or reel upon which the cloth is wound. Fig. 6 is a similar view of one of the blocks for engaging the opposite end of the bolt or reel upon which the cloth is wound. Fig. 7 is a sectional view on the line 7—7 of Fig. 2.

Corresponding and like parts are referred to in the following description and indicated in all the views of the drawings by the same reference characters.

Referring to the drawings, the numerals 1 and 2 designate the side pieces of the machine, the side piece 1 being provided at its opposite ends with the lateral extensions 3 which are slotted at 3^a to receive clamping nuts 4 carried by corresponding lateral extensions 5 upon the side piece 2. When the clamping nuts 4 are loosened the side pieces

1 and 2 may be drawn together or moved apart as required by the width of the cloth to be measured, while when the clamping nuts are tightened the two side pieces are held rigidly in position. The side piece 1 is also provided at its middle portion with a laterally projecting arm 6 which is disposed between the extensions 3 and projects beyond the side piece 2. This lateral arm 6 terminates in a standard 7 and journaled between bearings 8 upon this standard and the side piece 1 is a measuring roller 9, the middle portion of the side piece 2 being cut away or depressed at 2^a to provide a clearance for the measuring roller. Bearing blocks 10 are slidably mounted both upon the standard 7 and the side piece 1 and journaled between these bearing blocks is a tension roller 11 which is held in a yielding engagement with the measuring roller by means of the springs 12.

Rigidly applied to the pivot member at 75 one end of the measuring roller is a primary indicating disk 13 having a suitable scale marked thereon for coöperation with a pointer 14 to designate the amount of cloth measured by a partial revolution of the 80 roller, the cloth passing around the measuring roller between the same and the tension roller and the tension roller serving to hold the cloth against the measuring roller and to prevent any slipping thereof. The pivot 85 stud carrying the indicating disk 13 is also provided with a pinion 15 meshing with teeth upon the periphery of a secondary indicating disk 16 provided with a scale designed to coöperate with a pointer 17 to 90 indicate the number of yards of the cloth or fabric which have passed around the measuring roller. In the present instance the measuring roller has a circumference of one-half yard so that each revolution thereof 95 will measure a half yard of the cloth, and the primary indicating disk 13 is provided with a scale reading by one-sixteenths from "zero" to "one-half." The scale upon the secondary indicating disk 16 reads from 100 "zero" to "seventy" and coöperates with the pointer 17 to designate the number of whole or half yards which have passed around the measuring roller, a detent 18 being provided to prevent the secondary indicating disk mov-

ing more than one tooth at a time. The opposite ends of each of the side pieces 1 and 2 are extended upwardly at 1^b and 2^b respectively and applied to these upwardly extended portions of the side pieces are the bushings 19. The reel or bolt from which the cloth is to be measured is mounted between the upward extensions at one end of the machine while the reel or bolt upon which the cloth is to be wound after being measured is journaled between the upward extensions at the opposite end of the machine. Threaded within one of the bushings 19 at each end of the machine is a screw 20, the outer end of the screw being formed with a handle 20^a while the inner end has a block 21 swiveled thereon. These blocks 21 are shown as forked and are designed to engage one end of the bolt or reel as indicated on the drawing. Journaled within the opposite bushing of each pair is a shaft 22 carrying a block 23 similar to the blocks 21, one of the shafts having a handle 24 applied thereto.

25 In the operation of the machine the side pieces 1 and 2 are adjusted to accommodate the reel or bolt to be measured and the bolt upon which the cloth is wound is secured between the blocks 21 and 23 at one end of the machine. In this connection it may be mentioned that by turning the screws 20 to move the blocks 21 outwardly the bolts may be released, while by turning the screws in the opposite direction and moving the blocks 35 inwardly the bolts will be securely clamped in position. The cloth is then threaded between the measuring roller 9 and the tension roller 11 and attached to the bolt or reel to which it is to be wound. By turning the handle 24 the cloth may then be drawn around the measuring roller and wound upon the second reel, the quantity of the cloth passing from the first bolt to the second bolt being accurately indicated by means 45 of the disks 13 and 16, the latter mentioned disk registering the number of full or half yards while the first mentioned disk registers any fractions of a half yard.

Having thus described the invention, what 50 is claimed as new is:

1. In a measuring machine of the character described, the combination of a pair of side pieces formed with corresponding lateral extensions which are adjustably connected, an arm projecting from one of the side pieces and provided with a standard, a measuring roller journaled between the said side piece and the standard, and reels journaled between the side pieces.

60 2. In a measuring machine of the character described, the combination of a pair of side pieces formed with lateral extensions having an adjustable connection, an arm projecting from one of the side pieces and

provided with a standard, the opposite side 65 piece being formed with a cut away portion, a measuring roller journaled between the first mentioned side piece and the standard and operating within the cut away portion of the second mentioned side piece, and reels 70 journaled between the side pieces.

3. In a measuring machine of the character described, the combination of a pair of side pieces formed with lateral extensions which are adjustably connected to admit of 75 the side pieces being moved toward or away from each other, reels mounted between the side pieces, blocks journaled upon the side pieces for engaging the reels, means for adjusting the blocks toward or away from each 80 other, and a measuring roller carried at one end by one of the side pieces and located between the reels, the cloth passing around the measuring roller as it is wound from one reel to the opposite reel. 85

4. In a measuring machine of the character described, the combination of a pair of side pieces formed with corresponding lateral extensions which are adjustably connected to admit of the side pieces being moved toward or away from each other, a lateral arm projecting from one side piece and provided with a standard, the opposite side piece being formed with a cut away portion, a measuring roller journaled between 90 the first mentioned side piece and the standard and operating within the cut away portion of the second mentioned side piece, indicating disks actuated by the measuring roller, pointers coöperating with the indicating disks to register the length of the cloth passed around the measuring roller, and reels journaled between the side pieces, the cloth passing around the measuring roller as it is wound from one reel upon the 95 opposite reel. 100

5. In a measuring machine of the character described, the combination of side pieces, means for adjustably connecting the side pieces to admit of their being moved toward 110 or away from each other, a lateral arm projecting from one side piece and provided with a standard, a measuring roller journaled between the standard and the said side piece, a tension roller also journaled between the standard and the side piece and bearing yieldingly against the measuring roller, and reels journaled between the side pieces, the cloth passing around the measuring roller as it is wound from one reel upon 115 the opposite reel. 120

6. In a measuring machine of the character described, the combination of a pair of side pieces, means adjustably connecting the side pieces to admit of their being moved 125 toward or away from each other, a lateral arm projecting from one side piece and extending beyond the opposite side piece, the

said lateral arm being formed with a standard, a measuring roller journaled between the standard and the said side piece, and reels journaled between the side pieces, the cloth passing around the measuring roller as it is wound from one reel upon the opposite reel.

In testimony whereof I affix my signature in presence of two witnesses.
